UNITED STATES PATENT OFFICE.

TALBOT C. DEXTER, OF PEARL RIVER, NEW YORK.

PAPER-FEEDING MACHINE.

No. 850,821.

Specification of Letters Patent.

Patented April 16, 1907.

Application filed August 9, 1906. Serial No. 329,898.

To all whom it may concern:

Be it known that I, TALBOT C. DEXTER, a citizen of the United States, and a resident of Pearl River, in the county of Rockland and State of New York, have invented certain new and useful Improvements in Paper-Feeding Machines, of which the following is a specification.

My present invention relates to improvements in paper-feeding machines of the sheet-combing type, in which the pile of sheets is acted upon by combing feeding devices which comb or feather out the top sheets of the pile to gradually separate the successive sheets near the top, so they may be drawn from the pile periodically and fed to any machine arranged to operate upon the individual sheets. A machine of this type is set forth in Letters Patent No. 829,854, granted to me August 28, 1906, and my present invention may best be considered in the light of an improvement upon the machine covered by the said patent.

My present invention relates to improved features of construction particularly with reference to the mechanism for raising and lowering the sheet-combing devices and the sheet-actuated, tripping devices which control the operation of the combing devices.

In order that my invention may be fully understood, I will first describe the same with reference to the accompanying drawings and afterward point out the novelty more particularly in the annexed claims.

Figure 1 is a sectional plan view of a paper-feeding machine embodying my invention, parts being broken away and omitted. Fig. 2 is a vertical longitudinal sectional view of the same, the section being taken on the lines 2-2 of Fig. 1. Fig. 3 is a front elevation of the parts of the machine shown in Figs. 1 and 2. Fig. 4 is a detail vertical longitudinal sectional elevation showing the arrangement of the comber elevating and lowering mechanism. Fig. 5 is a detail view of the same mechanism looking from the front of the machine. Fig. 6 is a detail side elevation of the driving part of the comber-controlling mechanism looking from the outside of the machine. Fig. 7 is a detail vertical longitudinal sectional view of the sheet-actuated part of the comber-controlling mechanism. Fig. 8 is a detail elevation of the combined rack and ratchet-bar and its supporting-bracket, the positively-driven reciprocating carriage and rack being omitted. Fig. 9 is a detail sectional view illustrating the driving connec-

tion with the reciprocating carriage. Figs. 10, 11, and 12 are enlarged detail views of the sheet-controlled clutch mechanism which throws the combing device out of operation. 60

Sheet-combing feeding-machines of the type to which my present invention relates are provided with two sets of sheet-combing devices arranged to operate at opposite sides of the machine. In the accompanying drawings I have shown only one-half of the machine, including only one of these sheet-combing devices; but it will be understood that two combing devices of the same construction are employed, each being independently controlled by a sheet-actuated tripping mechanism in the manner well understood in this type of machine.

The framework of my improved machine may be of any suitable construction to properly support the working parts hereinafter referred to.

In the drawings, 11 represent the vertical side frames. These side frames are suitably braced to make them rigid by means of stay-rods 23 and other frame parts, (not shown,) and within the frame is provided a suitable table or support for carrying a pile of sheets, (indicated by the reference-letter P.) At the front of the pile of sheets I provide a series of vertical guide rods or strips (not shown) for confining the pile. 85

5 is a constantly-driven shaft bearing the lower feed-rollers 6, said shaft 5 being braced at intervals by suitable bearing-brackets. 90 (Not shown.)

8 are drop-rollers journaled in the bifurcated rock-arms 9, mounted upon the transverse rock-shaft 10. The rock-arms 9 are preferably shaped to form sheet confining or guiding fingers, as shown. The rock-shaft 10 extends transversely of the machine, above the constantly-running lower shaft 5, and is suitably braced between its ends by two or more bracket-arms 11, rigidly secured to the auxiliary longitudinal frame-pieces 12. The rock-shaft 10 is operated by the usual mechanism, whereby the series of drop-rollers 8 are periodically raised and lowered for performing their function. 105

21 and 22 are respectively the under feed-roller and drop-roller of a folding-machine to which the feeder is to pass the sheets.

The main cam-shaft 20 extends transversely of the machine and is suitably journaled in the main side frames 1 and the auxiliary longitudinal frame-pieces 12. This

shaft 20 is provided with a driving-pulley 25, as shown, or it may be driven in any other suitable manner, said shaft being the shaft from which all other parts of the machine are driven. The cam-shaft 20 carries a large gear 26, which meshes with a smaller gear 27, secured to a larger gear 28, journaled upon a stud 29, projecting from the side frame of the machine. The gear 28 meshes 5 with and drives a smaller gear 30, journaled upon a stud 31, projecting from the side frame of the machine, and this gear 30 in turn drives a smaller gear 32, keyed to the projecting end of the comber-driving shaft 35, hereinafter referred to, and a smaller gear 33, keyed to the projecting end of the constantly-rotating feed-shaft 5, above referred to.

40 is one of a pair of combing-wheels. Each of these combing-wheels is freely journaled at 41 upon a rock-arm 42, which is freely journaled upon a sleeve 50, which is in turn journaled upon the shaft 35. This shaft 35 (driven by gear 32) has keyed to it a gear 45, which meshes with a gear 46, secured to the combing-wheel 40, by which the combing-wheel is constantly rotated.

Projecting from one face of the comber-supporting rock-arm 42 is an integral lug 43, in which is mounted an adjustable tappet-screw 44. Secured upon the sleeve 50 to one side of the rock-arm 42 is a rock-arm 51, which is provided with a finger 52, which projects beneath the tappet-screw 44, just referred to, and by its engagement therewith lifts the combing-wheel away from the pile. By adjusting the screw 44 the limits of rise and fall of the combing-wheel can be fixed.

The rock-arm 51 is moved in one direction for lifting the combing-wheel by a spring mechanism which is released by the sheet-actuated tripping device hereinafter explained. The rock-arm 51 is moved in the opposite direction to allow the combing-wheel to move by gravity into engagement with the pile of sheets by the action of a cam, as will now be explained.

Sleeve 50 has at its end adjacent to the rock-arm 51 another rock-arm 55, to which is pivotally connected a pitman 56, formed 50 with a yoke-shaped upper end, which straddles the shaft 20. The shaft 20 carries a peripheral cam 58, which engages the antifriction-roller 57, journaled upon the pitman 56, whereby the rock-arm 55, sleeve 50, and finger 52 are moved once in each revolution of the shaft 20 to reset the tripping mechanism hereinafter described and allow the combing-wheel to rest upon the pile. The rock-arm 51 projects forwardly from the sleeve 50 55 and has pivotally connected to its forward end a yoke-shaped latching-bar 60, extending vertically and formed at its upper end with a contracted guide-bar portion 60^a, which rides in a socket 61, formed in a bracket 62, extending laterally from one of

the central auxiliary frames 12. Pivoted at 63^a in the upper end of the loop of the yoke-shaped latching-bar 60 is a toggle-link 63, which is pivotally connected at its lower bifurcated end by pivot-pin 64^a with the upper 70 bifurcated end of the lower toggle-link 64. The toggle-link 64 is pivotally mounted at its lower end upon a pivot-pin 64^b, between ears 65^a, extending from an angular bracket-arm 65, which is secured to one of the frame-pieces 12. The ears 65^a project within the loop of latching-bar 60, so as to support the lower end of the lower toggle-link therein and maintain the thrust of the toggle in line with bar 60. The purpose of the latching-bar 60 and toggle-links 63 80 64 is to retain the rock-arm 51 and the spring device connected thereto (presently to be referred to) in position to allow the operation of the combing-wheel. 66 is an antifriction-roller journaled 85 upon pin 64^a.

I will now proceed to describe the spring device and will afterward explain the mechanism for releasing the latching mechanism under the control of the sheets fed from the pile. A rod 70 is pivoted at 71 to the rock-arm 51 and projects therefrom vertically through a guide-pin 72, projecting from the bracket 62. Surrounding the rod 70 and confined between the rock-arm 51 and guide-pin 72 is an expansion-spring 75, which tends to throw down the arm 51 and move up the finger 52 for raising the comber away from the pile of sheets. This spring tendency is normally restrained by the toggle-links 63 64 90 and the latching-bar 60.

Turning now to the sheet-actuated tripping mechanism for controlling the operation of the combing devices, I will first refer to the clutch mechanism which trips the spring-controlled latching mechanism under the action of the sheet-actuated tripper, then the means for operating the mechanism, and finally the structure and operation of the tripping device. Each of the auxiliary 105 frame-pieces 12 is formed with a vertical dovetail guideway 80, in which is mounted a vertically-reciprocating bracket-plate 81, upon which are mounted the sectional clutch-shaft, the operating-rack, and the tripping-rack hereinafter referred to. This bracket-plate 81 is formed with a vertical guide-slot 82, fitting over the cam-shaft 20 and allowing the vertical movements of the bracket-plate 81. An antifriction-roller is journaled upon 110 a stud 84, projecting from one face of the plate 81, and cam 85 is keyed to the shaft 20 in position to engage the antifriction-roller 83 and support the plate 81 and intermittently raise and lower it.

Bracket-arms 90 are secured to and project rearwardly from the plate 81 in position to support the sectional clutch-shaft consisting of members 91 and 92. (Illustrated in detail in Figs. 10 and 11 of the drawings.) The 125

clutch-shaft members 91 and 92 are of hollow or tubular form, each one being suitably journaled in one of the arms of the bracket 90. The shaft member 91 in addition to being 5 movable about its axis is capable of moving longitudinally in its bearing 90. This member 91 has mounted upon it or formed integral with it a gear-wheel 93 (driven by rack hereinafter referred to) and one member 94 10 of a cam-faced slip-clutch formed in its working face with a plurality of radial cam-faced recesses 94^a. The other tubular shaft member 92 has mounted upon one end or formed integral therewith a gear-wheel 95 15 (driving a movably-mounted combined rack and ratchet bar hereinafter referred to) and upon its opposite or inner end the other member 96 of the slip-clutch, formed upon its working face with a plurality of radial cam-faced ribs or lugs 96^a. Secured within the hollow shaft member 91 is a tube 100, which projects from the hollow shaft member 91 20 into the hollow shaft member 92. This tube 100 is brazed or otherwise rigidly secured in the threaded nut or thimble 101, which is screwed into a threaded counterbore or recess formed in the inner end of the hollow shaft member 91. The end of the tube 100 which projects into the hollow shaft member 92 25 is partly closed by a ring or washer 102, secured in the end of the tube and having a central opening through it. A bolt 103, having a cylindrical head 104, is passed through the central opening of the ring or washer 102 30 and through an opening 99 in the gear-wheel 95 and supports an expansion-spring 105, which is confined between the washer 102 and the cylindrical head 104, the outer threaded end of the bolt being engaged by 35 the nuts 106 and 107. The tension of the spring 105 can be regulated by adjusting the nuts upon the bolt. It will be observed from this construction that the spring 105 tends to hold the two parts of the clutch 40 94 96 in engaged position, so that the gear-wheel 95 will be rotated from the gear 93 through the hollow shaft-sections 91 92. The bracket-bearing 90 supports the sectional clutch-shaft 91 92 transversely of the machine and approximately in line with the knuckle-joint connecting the toggle-links 63 64, the toggle-links extending across the line of the hollow sectional shaft, so that any longitudinal movement of the shaft-section 91 45 toward the toggle-levers will engage roller 66 and force the knuckle of the toggle-levers outwardly, thereby breaking the toggle-latch and allowing the spring-actuated rod 70 to raise the combing-wheel from the pile 50 of sheets. This movement of the shaft-section 91 is effected by arresting the rotation of the shaft-section 92, which is accomplished through the medium of the sheet-actuated tripping devices hereinafter referred to.

45 The vertically-reciprocating bracket-plate

51 carries at its lower end a rearwardly-projecting dovetail track-bar 110, upon which is mounted a horizontally-reciprocating carriage 111, having secured to its upper edge a rack-bar 112, which is in constant mesh with the gear-wheel 93 upon shaft member 91. The carriage 111 is constantly reciprocated forwardly and backwardly by means of a rock-arm 115, depending from a rock-shaft 116 and pivoted at its lower end to a link 117, which link carries at its forward end a pivot-pin 118, which is journaled in the forward end of link 117 and has pivotal connection, as shown at 119 in Fig. 9, with a lug upon the carriage 111. A nut 120 confines 80 the pin upon the carriage 111.

The rock-shaft 116 is suitably journaled in the machine-frame and extends from side to side of the machine. This rock-shaft 116 carries at its outer end a depending rock-arm 121, pivoted at its lower end 122 to a link 123, which is in turn pivoted at 124 to a slotted rock arm or lever 125. This rocker-arm 125 is journaled at 126 to bracket 127, secured to the machine-frame, and is formed with a longitudinal slot 125^a, in which operates an antifriction-roller 128, journaled upon a crank pin or stud 129, projecting from the face of the crank-disk 130, which is keyed to one end of the cam-shaft 20. The track-bar 95 110 is provided upon its outer face—that is, upon the face opposite to the carriage 111—with angular brackets 135, upon which are supported a combined rack and ratchet bar 136. The forward half of this bar 136 is formed at its upper edge with rack-teeth 136^a, (see Fig. 8,) which are in constant mesh with the gear-wheel 95 on sectional shaft member 92, so that the movement of the shaft member 92 about its axis will be 100 transmitted to the bar 136 and cause said bar to reciprocate upon its supports. The rear half of the bar 136 is formed upon its upper edge with ratchet-teeth 136^b for the purpose presently to be explained. The combined rack and ratchet bar is also formed with a longitudinal slot 136^c, into which projects a portion 118^a of the pin 118 for the purpose hereinafter explained. The track-bar 110 is also formed with an upwardly-projecting longitudinal flange 110^a, having a slot 110^b, corresponding in position with the slot in the combined rack and ratchet bar when the latter is in its initial position for starting, pin 118^a projecting through the slot 110^b into the slot of the combined rack and ratchet bar. This slotted flange 110^a serves as a guide for the combined rack and ratchet bar and for the pin 118 in their reciprocating movement. 136^e is a stop-pin on bar 136.

140 is a downwardly-projecting bracket-arm, to the lower end of which is journaled a sheet-actuated tripping-finger 141, which is supported in the path of the sheet just above the constantly-rotating underfeed-roller 130.

shaft 5. This tripping-finger 141 is preferably of U shape, with its two arms projecting upon opposite sides of one of the underfeed-rollers 6. The heel 141^a of the tripping-finger 141 is connected through rod 142 with a pawl 143, which is journaled at 144 on the upwardly-projecting lug 145 of the supporting-bracket, this pawl 143 being supported in the same vertical plane as the ratchet-teeth 136^b of the combined rack and ratchet bar 136.

Extending longitudinally of the machine at each side is a rock-shaft 155, journaled in bracket-arms 156, extending down from the auxiliary frame-pieces 12. At the forward end of each of these rock-shafts is a rock-arm 157, carrying at its upper end an antifriction-roller 158, which operates in engagement with a face-cam 159, keyed to the cam-shaft 20. Each of the rock-shafts 155 carries a horizontal rock-arm, which is adjustable longitudinally of the machine and carries a weighted tail-gripper 160 of the same construction as fully set forth in my above-named patent.

The following brief explanation will make clear the operation of my improved machine: It being understood that a machine embodying my improvements is provided with two sets of sheet-combing mechanisms, each independently controlled by a sheet-actuated tripping mechanism as described, the machine is started in operation with the combing-wheels resting upon the top of the pile of sheets, the combing-wheels being driven through the gears, as above explained, and the trip-fingers 141 resting in the path of the sheets and the pawls 143 being supported thereby out of engagement with the ratchet-bars 136, so that the ratchet-bars will reciprocate freely through the medium of clutch mechanism 94 96, driven by the rack-bar 112. In this normal operative position of the machine the spring-elevating mechanisms for the combers are held out of action by the toggles 63 64 and latching-bars 60. The combing-wheels will operate until the top sheet is moved forward sufficiently to actuate one of the trip-fingers 141, which action will drop one of the pawls 143 into engagement with a ratchet-bar 136, arresting said ratchet-bar, and thereby causing the disengagement of clutch members 94 96 with the consequent longitudinal displacement of shaft-section 91. The movement of shaft-section 91 breaks toggle 63 64 of the latching-bar 60, which allows the spring 75 to act for raising the first combing-wheel from the pile. This action is immediately followed by the same operation on the other combing-wheel as the edge of the sheet in front of such combing-wheel reaches registered position. Immediately following the arrest of the two combing-wheels the cams 85 come into play to raise trip-fingers 141

out of the path of the sheets, (the rack-bars and sectional clutch-shafts being raised also,) and then the drop-roller mechanism operates for feeding the sheet off from the pile. As the sheet is engaged by the drop-roller mechanism the tail-grips 160 engage the under sheet just back of the rear edge of the top sheet for holding the pile. As soon as the sheet has left the pile the cams 85 again lower the frames 81 110 for returning the trip-fingers 141 and the rack-bars and sectional clutch-shafts to their lowered position ready for another feeding operation. At about the same time the driving rack-bars 112 and combined rack and ratchet bars 136 are returned rearwardly of the machine. These rack-bars move rearwardly simultaneously until the pin 136^c of the movable rack-bar 136 engages its supporting frame or bracket and arrests its movement, the pin 118^a sliding in the slot 136^c until the end of the rearward stroke of the carriage 111 is reached, when the parts will be in readiness for another forward feeding stroke. The return of the part to this initial position will of course cause the relative shifting of the clutch members 94 96. Immediately following this operation the cams 58 forcibly rock the sleeves 50 for allowing the combing-wheels to again fall into engagement with the top of the pile of sheets and at the same time to reset the toggle-levers 63 64, moving them into the position shown in Fig. 3. It will be observed that in this reset position the toggle-links are moved inwardly a little out of line, so as to latch them in this position, the antifriction-roller 66 at the knuckle-joint of the toggles resting in contact with the end of the shaft-section 91.

I would have it understood that the structure of my improved machine as above described is subject to many of the claims of my above-named patent on this same type of machine, the present application being limited to the differences in construction of the controlling and tripping mechanisms of the combing devices.

Having thus described my invention, the following is what I claim as new therein and desire to secure by Letters Patent:

1. In a paper-feeding machine, the combination of a sheet-moving device, and means for operating the sheet-moving device, of a rock-arm adapted to engage and elevate the sheet-moving device, a spring mechanism tending to move said rock-arm in one direction, mechanism adapted to periodically move the rock-arm in the opposite direction, a latching-bar connected with the rock-arm, toggle-levers engaging the latching-bar and retaining the rock-arm in one position with the spring mechanism under tension, and sheet-actuated means adapted to trip said toggle-levers to allow the spring mechanism to operate.

2. The combination of a support for a pile of sheets, a rotary shaft, a rotary sheet-moving instrument driven from said shaft and adapted to engage the top of the pile of sheets, a rock-arm supporting the rotary sheet-moving instrument, a second rock-arm adapted to raise and lower the sheet-moving instrument, cam mechanism suitably connected with said second rock-arm, a spring device also connected with said second rock-arm, a latching-bar connected with said second rock-arm, toggle-levers connected respectively with said latching-bar and a stationary part of the machine-frame, and sheet-actuated means adapted to trip said toggle-levers for releasing said spring mechanism.

3. The combination of a sheet-moving instrument adapted to be moved into and out of engagement with the sheet, a spring device adapted to elevate the sheet-moving instrument, a latching-bar having toggle-levers for restraining the action of the spring device, a longitudinally-movable throw-out shaft adapted to trip said toggle-levers, and sheet-controlled mechanism for effecting the longitudinal movement of the throw-out shaft.

4. The combination of a sheet-moving instrument adapted to be moved into and out of engagement with a sheet, a spring device adapted to elevate the sheet-moving instrument, a latching-bar for restraining the action of the spring device, toggle-levers connecting the latching-bar with a stationary bracket, a longitudinally-movable throw-out shaft adapted to release said restraining means, sheet-controlled mechanism for effecting the longitudinal movement of the throw-out shaft, and cam mechanism adapted to reset the restraining means.

5. In a paper-feeding machine, the combination of a sheet-moving device, and means for operating said device, with a rock-arm adapted to elevate the sheet-moving device, a spring mechanism connected with said rock-arm and adapted to move it in one direction, a latching-bar also connected to said rock-arm, a bracket-arm, toggle-levers connecting respectively with said latching-bar and said bracket-arm, and sheet-actuated means adapted to trip said toggle-levers.

6. In a paper-feeding machine, the combination of a sheet-moving device, and means for operating said device, with a rock-arm adapted to elevate the sheet-moving device, a spring mechanism connected with said rock-arm and adapted to move it in one direction, a latching-bar also connected to said rock-arm, said latching-bar being in the form of an elongated yoke or loop, a bracket-arm projecting into the loop of the latching-bar, pivotally-connected toggle-levers pivoted respectively to the latching-bar and bracket-arm, and sheet-actuated means adapted to trip said toggle-levers.

7. In a paper-feeding machine, the combi-

nation of a sheet-moving device, and means for operating said device, with a rock-arm adapted to elevate the sheet-moving device, a spring mechanism connected with said rock-arm and adapted to move it in one direction, a latching-bar also connected to said rock-arm, said latching-bar being in the form of an elongated yoke or loop, a bracket-arm projecting into the loop of the latching-bar, pivotally-connected toggle-levers pivoted respectively to the latching-bar and bracket-arm, an antifriction-roller journaled upon the knuckle-joint of said toggle-lever, a longitudinally-movable throw-out shaft adapted to engage said antifriction-roller, and sheet-actuated means adapted to cause said shaft to move longitudinally for tripping said toggle-levers.

8. In a paper-feeding machine, the combination of a sheet-moving device and means for operating said device, with suitable throw-out mechanism comprising a sectional shaft, a slip-clutch connecting said shaft-sections, means for operating said sectional shaft, a gear secured to one of said shaft-sections, a rack-bar meshing with and driven by said gear, and sheet-actuated means for arresting the movement of said driven rack-bar.

9. In a paper-feeding machine, the combination of a sheet-moving device and means for operating the said device, with throw-out mechanism for said sheet-moving device including a sectional shaft, a slip-clutch connecting the sections of said shaft, gear-wheels secured to said shaft-sections, a positively-driven rack-bar meshing with the one of said gears for driving said shaft, a second rack-bar meshing with and driven by the other gear-wheel, and sheet-actuated means adapted to arrest the movement of said driven rack-bar.

10. In a paper-feeding machine, the combination of a sheet-moving device and means for operating said device, with means for moving the sheet-moving device out of operation including a longitudinally-movable shaft-section carrying a gear-wheel, a rack-bar meshing with said gear-wheel and driving said shaft-section, means for operating said rack-bar, a second shaft-section carrying a second gear-wheel, slip-clutch members mounted upon the respective shaft-sections, a combined rack and ratchet bar the rack portion of which meshes with said second gear-wheel, a controlling-pawl, and a sheet-actuated finger suitably connected with said pawl.

11. The combination of a sheet-support, a sheet-moving instrument, means for elevating the sheet-moving instrument, a shaft-section movable longitudinally and about its axis, means actuated by the longitudinal movement of said shaft-section for releasing the elevating means, a second shaft-section

- movable about its axis, slip-clutch members secured upon the respective shaft-sections, means acting upon one of said shaft-sections for moving both shaft-sections about their 5 axis, a gear upon the other section, a rack-bar meshing with and driven by said gear, and sheet-controlled means acting upon the rack-bar for the purpose set forth.
12. The combination of a sheet-support; a sheet-moving instrument, means for elevating the sheet-moving instrument, a shaft-section movable longitudinally and about its axis, means actuated by the longitudinal movement of said shaft-section for releasing 10 the elevating means, a second shaft-section movable about its axis, slip-clutch members secured upon the respective shaft-sections, a gear mounted upon one of said shaft-sections, a positively-driven reciprocating rack 15 meshing with said gear for moving both shaft-sections about their axis, a second gear upon the second shaft-section, a rack-bar meshing with and driven by said second gear, and sheet-controlled means acting upon the 20 rack-bar to arrest the movement of one shaft-section about its axis and cause the other shaft-section to move longitudinally.
13. The combination of a sheet-moving instrument, means for elevating the sheet-moving instrument from a pile, a rotary longitudinally-movable shaft-section, means actuated by the longitudinal movement of said shaft-section for releasing the elevating means, a second rotary shaft-section, slip-clutch members secured upon the respective rotary shaft-sections, means yieldingly connecting the shaft-sections, a gear-wheel upon 35 each of said rotary shaft-sections, a stationary track bar or frame, a reciprocating carriage mounted upon the track-bar, and carrying a rack-bar which meshes with one of said gears for driving said sectional shaft, a 40

combined rack and ratchet bar also mounted upon said track bar or frame and meshing with the other gear, and a sheet-actuated 45 pawl adapted to engage said ratchet.

14. In a paper-feeding machine, the combination of a sheet-moving device and means for operating said device, with means for moving the sheet-moving device out of operation including a longitudinally-movable shaft-section carrying a gear-wheel, a rack-bar meshing with said gear-wheel and driving said shaft-section, a reciprocating link operating said rack-bar, a second shaft-section 50 carrying a second gear-wheel, slip-clutch members mounted upon the respective shaft-sections, a slotted combined rack and ratchet bar, the rack portion of which meshes with said second gear-wheel, a pin projecting from 55 said link into the slot of said rack and ratchet bar, a controlling-pawl, and a sheet-actuated finger suitably connected with said pawl.

15. In a paper-feeding machine, the combination of a sheet-moving device and means for operating the said device, with throw-out mechanism for said sheet-moving device including a sectional shaft, a slip-clutch connecting the sections of said shaft, gear-wheels secured to said shaft-sections, the track-bar 60 110, the reciprocating carriage 111 carrying rack 112, the combined rack and ratchet bar 136 formed with slot 136^a, a stop for limiting the movement of bar 136 in one direction, the link 117, pin 118, connecting the carriage 70 and link and engaging the slot 136^b, means for imparting movement to link 117, and a sheet-controlled pawl adapted to engage the ratchet.

TALBOT C. DEXTER.

Witnesses:

G. V. P. LEITCH,
E. B. O. LINDQUIST.
